UNITED STATES PATENT OFFICE.

JOHN B. BAXTER, OF TROY, NEW YORK, ASSIGNOR TO COVERT MANUFACTURING CO.,
OF TROY, NEW YORK, A CORPORATION OF NEW YORK.

SPRING-TONGUE SNAP HOOK.

Application filed December 8, 1920. Serial No. 429,126.

To all whom it may concern:

Be it known that I, JOHN B. BAXTER, citizen of the United States, residing at Troy, in the county of Rensselaer and State 5 of New York, have invented certain new and useful Improvements in a Spring-Tongue Snap Hook, of which the following is a specification, reference being had therein to the accompanying drawing.

10 My invention relates to improvements in spring tongue snap hooks and more particularly to a hook of this character embodying a substantially **U** shaped spring tongue adapted to be connected to the body.

15 The principal object of the invention resides in a novel manner of casting or forming the body so that the tongue may be easily and securely connected thereto.

Another object consists in forming the 20 body, and connecting the spring tongue thereto, in such a manner that the hook may engage a ring or other object at opposite ends.

With the above and other objects in view 25 which will appear as the description proceeds my invention consists in the novel details of construction and arrangement of parts which will be clearly understood from the following specification and drawings, 30 and while I have illustrated and described the preferred embodiment of the invention it will be understood that such changes may be made as will fall within the scope of the appended claims.

35 In the drawings:—

Figure 1 is a bottom plan of the body prior to inserting and securing the spring tongue,

Figure 2 is a longitudinal section through 40 the body shown in Figure 1,

Figure 3 is a bottom plan with the spring tongue in position,

Figure 4 is a longitudinal section through the body and spring tongue,

45 Figure 5 is a bottom plan showing a slightly modified form of body,

Figure 6 is a longitudinal section through that form of body illustrated in Figure 5 with the spring tongue attached,

50 Figure 7 is a fragmental longitudinal section of a still further modified form of body with the spring tongue attached; and

Figure 8 is a transverse vertical section on the line 7—7 of Figure 7 looking in the 55 direction of the arrows.

In carrying out my invention the body of the hook is cast with shank 1 having a bill 2 formed on one end and a frame structure on the opposite end for attaching the spring tongue. The hook is cast with the bill offset laterally, with respect to the shank, to facilitate its removal from the mould. In casting if desired a core may be used although this is not necessary. The frame structure comprises the two sides or cheeks 3, the outer ends of which are bent at right angles as shown at 4 and connected by a cross bar 5. The cross bar has a flange 6 on each edge for a purpose to be later described. A lug 7 is formed on the inner face of each side or cheek 3, preferably at the point where the ends are bent at right angles, and a lip or projection 8 extends from the shank 1 into the frame structure. The lip or projection 8 is of less thickness than the shank so as to form a shoulder 9 as more clearly shown in Figures 2 and 4 of the drawings.

In casting the sides or cheeks 3 are spread a substantial distance apart, as shown in Figure 1 of the drawings and in order to secure the spring tongue 10 in position the sides are pressed inwardly as more clearly shown in Figures 3 and 4. The spring tongue is of a substantially **U** shaped formation with the relatively short arm 11 and the long arm 12. The short arm 11 is used for connecting the spring to the body whereas the long arm 12 will co-operate with and engage the bill 2 to form the snap.

As previously stated when casting the sides 3 will be spread apart and to secure the spring 10 in the body the same will be placed in position with the end of the arm 11 engaging the top of the lip or projection 8 and the shoulder 9. The sides are then pressed inwardly until they engage the sides of the spring tongue with the lugs 7 engaging the upper face of the arm 11 of the spring as shown in Figure 4. The arm 12 will engage the under side of the cross bar 5 and be held between the side flanges 6 with its end engaging beneath the bill 2. When thus assembled the ends of the sides 3 will be bent as shown at 13 so as to engage the outer face of the spring tongue, adjacent the curved portion thereof, to prevent the said spring tongue from being slid from the end of the frame structure. It will be understood that after

the hook is cast the bill will be bent so as to extend parallel with the shank.

In Figures 5 and 6 of the drawings I have illustrated a slightly modified form of the invention. In this form the shank is shown at 14, the bill at 15, and the sides of the frame structure at 16. As in the preferred form the ends of the sides 16 are bent at right angles as shown at 17 and are connected by a cross bar 18 having the side flanges 19. Longitudinal spaced lugs 20 and 21 are formed on the inner face of each of the sides 16, the lugs 20 being adjacent the point where the ends of the sides are bent at right angles and the lugs 21 being adjacent the end of the lip or projection 22 extending from the shank into the frame structure. The lugs 21 will be slightly spaced from the upper face of the lip or projection 22 as more clearly shown in Figure 6 of the drawings, said space being equal to the thickness of the short arm 23 of the substantially U shaped spring tongue 24. The long arm 25 of the spring tongue engages the under side of the cross bar 18, between the side flanges 19, and its end engages beneath the bill 15. When the sides 16 are pressed inwardly to hold the spring tongue the lugs 20 and 21 will engage the top surface of the arm 23 and the ends of the sides 16 will be bent as shown at 26 to engage the curved portion of the spring tongue to prevent the same from being slid from the end of the frame. As shown in Figure 6 the lip or projection 22 is of less thickness than the shank so as to form a shoulder 27 to be engaged by the end of the arm 23 of the spring tongue. As in the preferred form of the invention the sides 16 will be cast spread apart and will be pressed inwardly to secure the spring tongue in the body. The only difference in the construction shown in Figures 1, 2, 3, and 4 and that shown in Figures 5 and 6 is that in the latter figures two lugs are formed on the inner face of each side instead of one, the additional lugs being used, when desired or necessary, to more securely connect the spring tongue to the body. A still further modified form of the invention is shown in Figures 7 and 8. In this form the sides of the frame structure are indicated at 28, the ends of the sides are bent at right angles as shown at 29, and are connected by the cross bar 30 having the side flanges 31. Instead of having lugs formed on the inner faces of the sides the sides are cut away to form the ridges or flanges 32 which extend longitudinally of the sides. In this form a portion of the substantially U shaped spring tongue is shown at 33 and is secured in position by pressing the sides 28 inwardly so that the ridges or flanges 32 engage the upper face of the arm 34 of the spring tongue. As in the other forms the

ends of the sides will be bent as shown at 35 to engage the outer face of the curved portion of the spring tongue to prevent it from being slid from the end of the body.

Having fully described the detailed construction of my hook it is thought that the advantages thereof will be clearly understood and it will be seen that when the parts are assembled and in position ready for use, that each end of the hook is curved so that a ring or other object may be received in each end. It is the principal object of my present invention to so cast the body that the spring may be easily inserted to position and secured. This is accomplished so by casting the body with the sides of the frame structure spread apart and in this formation the spring may be easily placed in position and then secured by pressing the sides inwardly to engage the edges of the spring with the lip or projection, formed on the shank, engaging one face of one of the spring arms and the lugs or ridges engaging the opposite face. The spring is held against displacement from the end of the body by pressing the ends of the side over the outer face of the curved portion of the spring tongue.

Having fully described my invention what I claim as new and desire to secure by Letters Patent is:

1. A snap hook of the character described comprising a shank having a bill on one end and a frame structure on the opposite end, said frame structure comprising sides which are normally spaced apart to form an open top and end, a projection extending from one side, a tongue formed on the shank and extending into the frame structure, said tongue being disconnected from the sides of the frame, and a substantially U-shaped spring tongue carried by the frame, one arm of the spring tongue adapted to engage the bill in the other arm adapted to engage the tongue which extends into the frame, the sides of the frame adapted to be moved inwardly to engage the edges of the arm of the spring tongue with the projection engaging the face of the arm opposite to that engaged by the tongue, and portions of the end of the frame being offset to overlie the outer face of the closed end of the spring tongue.

2. A snap hook of the character described comprising a shank having a bill on one end and a frame structure on the opposite end, said frame structure comprising sides which are normally spaced apart to form an open top and end, an inwardly extending projection formed on each side of the frame, a tongue formed on the shank and extending into the frame structure, said tongue being disconnected from the sides of the frame, and a substantially U-shaped spring tongue carried by the frame, one arm of the spring tongue

tongue adapted to engage the bill and the other arm adapted to engage the tongue which extends into the frame, the sides of the frame adapted to be moved inwardly to engage the edges of the arm of the spring tongue with the projections on the sides of the frame engaging the face of the arm opposite to that engaged by the tongue, and portions of the end of the frame being offset to overlie the outer face of the closed end of the spring tongue.

3. A snap hook of the character described comprising a shank having a bill on one end and a frame structure on the opposite end, said frame structure comprising sides which are normally spaced apart to form an open top and end and bent to form a hook portion of substantially the shape of the bill, a bar connecting the ends of the curved portion, a projection extending from one side, a tongue formed on the shank and extending into the frame structure, said tongue being disconnected from the sides of the frame, and a substantially U-shaped spring tongue carried by the frame, one end of the spring tongue engaging the bill and the bar connecting the ends of the curved portion of the frame, and the other arm engaging the tongue which extends into the frame, the sides adapted to be moved inwardly to engage the edges of the arm of the spring tongue with the projection engaging the face of the arm opposite to that engaged by the tongue, and portions of the end of the frame being offset to overlie the outer face of the closed end of the spring tongue.

4. A snap hook of the character described comprising a shank having a bill on one end and a frame structure on the opposite end, said frame structure comprising sides which are normally spaced apart to form an open top and end and bent to form a hook portion of substantially the shape of the bill, a bar connecting the ends of the curved portion, an inwardly extending projection formed on each side of the frame, a tongue formed on the shank and extending into the frame structure, said tongue being disconnected from the sides of the frame, and a substantially U-shaped spring tongue carried by the frame, one end of the spring tongue engaging the bill and the bar connecting the ends of the curved portion of the frame, and the other arm engaging the tongue which extends into the frame, the sides adapted to be moved inwardly to engage the edges of the

arm of the spring tongue with the projections engaging the face of the arm opposite to that engaged by the tongue, and portions of the end of the frame being offset to overlie the outer face of the closed end of the spring tongue.

5. A snap hook of the character described comprising a shank having a bill on one end and a frame structure on the opposite end, said frame structure comprising sides which are normally spaced apart to form an open top and end, a tongue formed on the shank and extending into the frame structure, said tongue being disconnected from the sides of the frame and of less width than the shank on which it is formed, and a substantially U-shaped spring tongue carried by the frame, one arm of the spring tongue being adapted to engage the bill and the other arm adapted to engage the tongue which extends into the frame, the width of the arm of the spring being greater than the tongue which it engages, the sides of the frame being adapted to be moved inwardly to engage the edges of the arm of the spring tongue.

6. A snap hook of the character described comprising a shank having a bill on one end and a frame structure on the opposite end, said frame structure comprising sides which are normally spaced apart to form an open top and end, a projection extending from one side of the frame, a tongue formed on the shank and extending into the frame structure, said tongue being disconnected from the sides of the frame and of less width than the shank on which it is formed, and a substantially U-shaped spring tongue carried by the frame, one arm of the spring tongue being adapted to engage the bill and the other arm adapted to engage the tongue which extends into the frame, the width of the arm of the spring being greater than the tongue which it engages, the sides of the frame being adapted to be moved inwardly to engage the edges of the arm of the spring tongue with the projection engaging the face of the arm opposite to that engaged by the tongue, and portions of the end of the frame being offset to overlie the outer face of the closed end of the spring tongue.

In testimony whereof I hereunto affix my signature in the presence of two witnesses.
